UNITED STATES PATENT OFFICE.

FRANK W. BERGER, OF WILLOW LAKES, SOUTH DAKOTA.

NECK-YOKE FASTENER.

1,393,487.

Specification of Letters Patent.

Patented Oct. 11, 1921.

Application filed May 21, 1919. Serial No. 298,741.

To all whom it may concern:

Be it known that I, FRANK W. BERGER, a citizen of the United States, residing at Willow Lakes, in the county of Clark and State of South Dakota, have invented certain new and useful Improvements in Neck-Yoke Fasteners, of which the following is a specification.

My invention relates to the general class 10 of carriages and wagons, particularly to neck-yoke securing means, and has for its object the provision of such means whereby a neck-yoke may be quickly and easily connected with or detached from the pole or tongue of a wagon or carriage or other vehicle or implement, such as reapers, binders, 15 mowers, plows, rakes and the like.

An important object is the provision of neck-yoke securing means which will operate to hold the neck-yoke more and more firmly in proportion to the pulling strain exerted thereon and on the pole or tongue but which will permit ready disengagement 25 of the neck-yoke from the pole or tongue upon reverse or rearward movement of the neck-yoke.

Another object is the provision of a device of this character which will be simple and inexpensive in manufacture, efficient in 30 use, durable in service, and a general improvement in the art.

With the above and other objects and advantages in view, the invention consists in the details of construction to be hereinafter 35 more fully described and claimed, and illustrated in the accompanying drawings, in which—

Figure 1 is a side elevation of the device in position upon a pole or tongue and engaged by a neck-yoke,

Fig. 2 is a similar view showing the device in releasing position,

Fig. 3 is a cross-sectional view, and Fig. 4 is a detail cross-sectional view.

Referring more particularly to the drawings, the letter A designates a pole or tongue and B designates a neck-yoke having an attaching ring C.

Secured upon the tongue is a metallic member including a portion 10 secured upon the top of the tongue and a portion 11 secured upon the under side of the tongue, these portions being connected by a curved bight 12 spaced from the end of the tongue.

Intermediate its ends, the portion 11 is pro-

vided with an extension 13 extending downwardly from the tongue.

Disposed beneath the tongue is a member 14 formed of somewhat resilient material which includes a portion 15 secured against the underside of the tongue by U bolts 16 and which is reflexly bent to provide a portion 17 extending forwardly of and in spaced relation to the tongue beyond the extension 13. At its forward end the portion 17 is curved, as shown at 18, to extend upwardly into engagement with the tongue and has formed thereon a forwardly extending handle 19 spaced beneath the end portion of the tongue. Formed at the juncture of 70 the handle 19 with the upwardly extending portion 18 is a rearwardly extending lip 20 which terminates adjacent the front of the extension 13 and which is curved to practically merge into the under side of the 75 tongue. The resilience of the member 14 is such that the lip 20 will be held against the tongue.

In the use of the device, the operator grasps the handle 19 and presses downwardly thereon whereupon the portion 17 of the member 14 will be sprung downwardly so that the lip 20 will be spaced from the tongue. The neck-yoke B is then attached to the tongue by slipping the ring C over the 85 metallic member secured at the end of the tongue until the ring passes between the tongue and the lip 20 and engages against the extension 13. The operator then releases the handle 19. When a forward pull 90 is subsequently exerted upon the neck-yoke B the ring C will engage the lip 20 and be prevented thereby from being disconnected from the tongue. To detach the neck-yoke 95 the handle 19 is moved downwardly and the ring C slipped off from the tongue.

From the foregoing description and a study of the drawings it will be apparent that I have thus provided extremely simple and readily operable means whereby a neck-yoke may be attached to or detached from a wagon tongue, the construction being such that the greater the forward pull upon the neck-yoke the greater will be the holding power of the means holding the neck-yoke. 105

While I have shown and described the preferred embodiment of the invention, it will be understood that I reserve the right to make such changes in the form, construction, and arrangement of parts as will not 110

depart from the spirit of the invention or the scope of the subjoined claims.

I claim:

In combination with a draft pole or tongue and neck-yoke, a neck-yoke fastener comprising a metallic member secured upon the end of the pole or tongue and having a downwardly extending projection spaced from the end thereof, a resilient member secured upon the pole or tongue and extending along the under side thereof in spaced parallel relation thereto and engaging against the end of said projection, the forward end of said resilient member being curved upwardly and rearwardly to define

a lip engaging against the under side of said metallic member forwardly of and adjacent the projection thereon, and a forwardly extending handle formed on the forward extremity of said resilient member adjacent its point of contact with said metallic member, said lip being engaged by the attaching ring of the neck-yoke when a forward pull is exerted and said projection being engaged by the ring when a rearward pull is exerted 25 upon the neck-yoke.

In testimony whereof I hereto affix my signature.

FRANK W. BERGER.
